[57] CLAIM

The ornamental design of an egg poacher, as shown and described.

DESCRIPTION

FIG. 1 is a front and side perspective view of an egg poacher showing my new design;

FIG. 2 is a bottom plan view of the egg poacher depicted in

FIG. 1;

FIG. 3 is a right side elevation view of the egg poacher depicted in FIG. 1, with the left side elevation view being a mirror image thereof;

FIG. 4 is a top plan view of the egg poacher depicted in FIG. 1;

FIG. 5 is a front elevation view of the egg poacher depicted in FIG. 1;

FIG. 6 is a rear elevation view of the egg poacher depicted in FIG. 1;

FIG. 7 is a front and side perspective view of the cover shown separately for ease of illustration;

FIG. 8 is a bottom plan view of the cover depicted in FIG. 7;

FIG. 9 is a top plan view of the cover depicted in FIG. 7;

FIG. 10 is a right side elevation view of the cover depicted in FIG. 7, with the left side elevation view being a mirror image thereof;

FIG. 11 is a front elevation view of the cover depicted in FIG. 7;

FIG. 12 is a rear elevation view of the cover depicted in FIG. 7;

FIG. 13 is a front and side perspective view of the body shown separately for ease of illustration;

FIG. 14 is a bottom plan view of the body depicted in FIG. 13;

FIG. 15 is a right side elevation view of the body depicted in FIG. 13, with the left side elevation view being a mirror image thereof;

FIG. 16 is a top plan view of the body depicted in FIG. 13;

FIG. 17 is a front elevation view of the body depicted in FIG. 13; and,

FIG. 18 is a rear elevation view of the body depicted in FIG. 13.
